UNITED STATES PATENT OFFICE.

CHARLES DUPUIS, OF CHARENTON, FRANCE.

PORTABLE APPARATUS FOR PROJECTING STATIONARY OR ANIMATED PICTURES.

1,137,958.

Specification of Letters Patent.

Patented May 4, 1915.

Application filed July 2, 1913. Serial No. 776,964.

To all whom it may concern:

Be it known that I, CHARLES DUPUIS, citizen of the Republic of France, residing at 22 Rue de la Cerisaie, Charenton, Seine, in the 5 said Republic, engineer, have invented certain new and useful Improvements in Portable Apparatus for Projecting Stationary or Animated Pictures; and I do hereby declare the following to be a full, clear, and 10 exact description of the invention, such as will enable others skilled in the art to which it appertains to make and use the same, reference being had to the accompanying drawings, and to letters or figures of reference 15 marked thereon, which form a part of this specification.

The invention has for its object an apparatus for projecting stationary or animated pictures, in which all the parts are brought 20 centrally close together and above a casing constituting the base (which can itself be covered by a removable cover) in a manner to cause as little encumbrance as possible, to be capable of being moved about very 25 easily and to be put in operation conveniently and rapidly.

This apparatus is characterized by the picture band (cinematographic film or band for independent stationary pictures) being 30 displaced in a horizontal direction before the exposure aperture, also horizontal, and by the light being produced from a source whose rays after traversing the exposed image in a vertical direction are reflected horizontally on to a screen. This reflection is obtained by means of a prism of the kind 35 giving total reflection, arranged in the base of the apparatus in front of a horizontal object glass; or if an object glass with very 40 short focus be used the glass can be placed advantageously in front of the prism. The rays emanating from the luminous source, which may be an electric or acetylene lamp or other suitable device, traverse 45 first of all a water bath for cooling purpose; this bath is closed at its upper part by a lens having a lower convex face, so as to obviate any agitation of the liquid surface and to drive toward the edges of the bath any 50 gaseous bubbles that the heat may give rise to.

The accompanying drawing shows all the details of an apparatus constructed according to this invention.

Figure 1 is a longitudinal section and Fig. 55 2 transverse axial section.

It will be seen from the drawing that the apparatus comprises a bottom casing or box 1, constituting the base, which is closed in front by a hinged door 1^a, while its top face 60 consists of a metal plate 2 carrying the whole of the mechanism. The image band is unrolled, as usual, from a bobbin 3 mounted on a horizontal axis or spindle 4 carried by an arm 5 articulated at its lower end on a support 6 on the plate 2. There is a take-up roll 7 whose axis or spindle 8 is carried by an arm 9 articulated on a support 10 on plate 2. Screws 11, adjustable in curved slots 12 of the supports 6 and 10, serve for 70 clamping the arms 5 and 9 in operative position or in a position suited for transport. The band unwound from bobbin 3 passes over the toothed cylinder 13 against which it is retained by small rolls or pins 14 carried by the articulated support 15; then, having made a bend, it passes horizontally 75 into a passage leading to the exposure aperture formed in a slide 16 adjustably mounted in an opening in plate 2 against which 80 said band is pressed by a spring shutter 17 articulated on the same plate. After leaving the exposure aperture, the band passes over toothed cylinder 18, against which it is pressed by small rollers 19 carried by the 85 movable shutter 17. Metal guides 20 direct, in the usual manner, the band on both sides of the exposure aperture. The band, after making a bend, then passes over another toothed cylinder 13^a, similar to cylinder 13, 90 and provided with rollers 14^a carried by the articulated support 15^a; it is then wound on the take-up bobbin 7 which is driven in a manner to be described hereafter. In Fig. 1, the path of the image band is indicated by 95 the dotted line 21.

The driving shaft 22, on which can be mounted the operating handle 23, is coupled by means of a train of gears 24, with the driving shaft 25 carrying the flywheel 26; 100 this latter shaft actuates, by means of intermittently operating mechanism, for example a Maltese cross gear 27, the spindle 28 of the feed or draw cylinder 18 in a manner to impart an intermittent advancing 105 movement to the band. The shaft 22 operates, by means of a train of gears 29, the spindle 30 of the toothed cylinder 13^a which

is attached to a chain wheel 31 which by means of chain 32 drives another chain wheel 31^a carried by the spindle of cylinder 13 in a way to effect the continuous feed. 5 of the band. The spindle 30 also carries a grooved pulley 33, which, by means of a cable or belt 34, which can be of metal, drives a similar pulley 35 mounted on shaft 8 of the bobbin 7. Pulley 35 is for this purpose 10 coupled to shaft 8 by a friction coupling, whose action is regulated by the tension of spring 36 in a way to allow the slipping of this pulley on the bobbin shaft in the case of an abnormal pull on the band occurring 15 which might cause it to break.

The objective device comprises a movable cylindrical portion 37 which contains the object glass and a stationary conical portion 38 which projects through one wall 20 of the case 1 and through which the luminous rays are projected onto the screen. On the inner end of the cylindrical portion 37 is arranged a total reflecting prism 39, the upper horizontal face of which is directly 25 below the exposure aperture. As stated above, the position of the objective glass can be modified if it has a very short focus and the exposure aperture may also be adjusted to center it exactly above the axis of the 30 prism 39. The slide 16 is mounted between guides (Fig. 2) on the underside of the plate 2 and is shifted by means of a rack and pinion 40, the rack on the slide being engaged by the pinion having a spindle 35 which projects outside the case where it is provided with a milled button 41. The cylindrical portion of the objective device is adjustable, from outside the case, by a rack and pinion 43, the pinion being on a spindle having a milled end 42 and engaging the 40 rack which is on said cylindrical portion 37.

The shutter 44 is mounted immediately above the object glass and prism, and is actuated by the shaft 25 by means of the 45 worm gear 45. The lantern 46 is arranged axially with respect to the exposure aperture 16; it is connected with a slide 47 movable on a vertical support 48, to which it can be clamped by a clamping screw 49. 50 Let it be supposed that an electric filament lamp, 50 of the Nernst type for example, be used and be arranged in the hinged cap 46^a of the lantern 46. Below the lamp is arranged a condenser 51 and below the latter is a water bath which consists of a receptacle 52 having a glass bottom and a plano-convex lens cover 53. As the receptacle is completely filled with water, agitation of the latter is prevented and the gaseous bubbles, set free by the heat, are directed toward the side of the receptacle by the convex face of the lens. In the base 1 55 is disposed an electric resistance 54, arranged in the leads 55 conducting current to lamp 50. At 55^a on the wall of the base

1 are indicated two terminals for the current for the luminous source.

The two bobbins 3 and 7 can be withdrawn from spindles 4 and 8 by turning down the articulated end parts 56 of these 70 spindles, which end part is turned up normally, in a manner to retain the bobbins in working position. The bobbins are locked to the spindles to insure rotation therewith by any suitable means. In the 75 form shown, the nave or hub 57 of the bobbin projects through the heads of the latter and has two notches formed in one end adapted to engage a pin 58 which projects transversely through the spindle. The 80 turned up end portion 56 prevents lateral movement of the bobbin and holds the notch end of the hub in contact with the pin as shown in Fig. 2.

When bobbins 3 and 7 have been withdrawn from their respective spindles, the arms 5 and 9 can be oscillated and be turned after the clamping screws 11 have been loosened, so that they approach the axis of the apparatus. If, at the same time 90 the lantern 46, 46^a be lowered by loosening its clamping screw 49 the whole upper part of the apparatus will give rise to little encumbrance, so that the whole can be covered by a cover 59 provided on its side 95 with spring lugs 60 which engage pins 61 carried by the opposite sides of the base 1. The handle 23 can be withdrawn from the shaft 22 and placed, for example, in the base, so as to allow of easy transport and 100 obviate all fear of damage to the mechanism.

The handle 23 if desired can be mounted directly on the driving shaft 25, the diameter of which with respect to the shaft 22 105 can be, for example, as 1 is to 8. This allows, in the case of stationary projections, of the band being advanced by one image only for each revolution of the handle, by thus determining exactly the point of the 110 cessation of the movement at the moment of the exhibition on the screen.

The above described apparatus is quite symmetrical, moreover the weight is concentrated at the lower part and is also uniformly distributed; besides this satisfactory feature, great stability is procured during the projection of animated pictures.

Having now described the nature of my 115 said invention and the best means I know of carrying the same into practical effect, I claim:

1. In an apparatus for the projection of stationary and animated pictures, a casing having an exposure aperture in its top, a standard mounted on the latter, a lamp adjustable on the standard perpendicular to the top and adapted to project light rays vertically through the aperture, reel supports pivotally mounted on the top and 120 125 130 135 140 145 150 155 160 165 170 175 180 185 190 adapted to be swung to and from the center of the latter, means to feed a picture film between the lamp and aperture, a total reflecting prism in the casing arranged to reflect the vertical light rays horizontally, and an object glass in the casing through which the horizontal rays are projected.

2. In an apparatus for the projection of stationary and animated pictures, a casing having an exposure aperture on its top, a lamp arranged to project light rays vertically through the aperture, a cooling device mounted between the lamp and aperture comprising a casing completely filled with liquid, a plano-convex lens closing the top of the casing with the convex face of the lens in contact with the liquid, means to feed a picture film between the cooling device and the aperture, a total reflecting prism in the casing arranged to reflect the vertical light rays horizontally, and an objective device in the casing through which the horizontal rays are reflected.

3. In an apparatus for the projection of stationary and animated pictures, a casing having an exposure aperture on its top, a lamp arranged to project light rays vertically through the aperture, a cooling device mounted between the lamp and aperture comprising a casing completely filled with liquid, a plano-convex lens closing the top of the casing with the convex face of the lens in contact with the liquid, means to feed a picture film between the cooling device and the aperture, a total reflecting prism in the casing arranged to reflect the vertical light rays horizontally, an objective device in the casing through which the horizontal rays are reflected, and means to adjust the exposure aperture relatively to the reflecting prism.

4. In an apparatus for the projection of stationary and animated pictures, a casing having an exposure aperture in its top, a lamp arranged to project light rays vertically through the aperture, a cooling device mounted between the lamp and aperture comprising a casing completely filled with liquid, a plano-convex lens closing the top of the casing with the convex face of the lens in contact with the liquid, means to feed a picture film between the cooling device and the aperture, a total reflecting prism in the casing arranged to reflect the vertical light rays horizontally, an objective device in the casing through which the horizontal rays are reflected, means to adjust the objective device, and means to center the aperture axially of the prism.

5. In an apparatus for the projection of stationary and animated pictures, a casing having an exposure aperture in its top, a lamp mounted on the latter and adapted to project light rays vertically through the aperture, means to adjust the lamp perpendicular to the top, reel supports pivotally mounted on the latter and adapted to be swung toward and from the center of the top, reels journaled in the supports, mechanism on the casing for continuously rotating the reels, a film on the reels, mechanism for intermittently moving the film over the aperture and means in the casing adapted to reflect the vertical rays horizontally.

In testimony that I claim the foregoing as my invention, I have signed my name in presence of two subscribing witnesses.

CHARLES DUPUIS.
